182,005

COMBINED WASHING MACHINE AND DRIER CABINET OR SIMILAR ARTICLE

Carl W. Sundberg, Birmingham, Mich., assignor to Whirlpool Corporation, a corporation of Delaware

Application August 13, 1956, Serial No. 42,591

Term of patent 14 years

(Cl. D49—1)

Fig. 1

Fig. 2

Fig. 3

Fig. 4

Fig. 5

Fig. 6

Figure 1 is a view in perspective of a combined washing machine and drier cabinet showing my new design;

Figure 2 is a front elevational view of the cabinet;

Figure 3 is a side elevational view of the machine;

Figure 4 is a fragmentary cross-sectional view taken along the line IV—IV of Figure 1;

Figure 5 is a fragmentary cross-sectional view taken along the line V—V of Figure 1; and

Figure 6 is a fragmentary cross-sectional view taken along the line VI—VI of Figure 2.

I claim:

The ornamental design for a combined washing machine and drier cabinet or similar article, substantially as shown.
